UNITED STATES PATENT OFFICE.

JAMES SCRIPPS BOOTH, OF DETROIT, MICHIGAN.

CHARGING AND DISTRIBUTING DEVICE FOR INTERNAL-COMBUSTION ENGINES.

Original application filed November 6, 1924. Serial No. 748,119. Divided and this application filed November 30, 1925 Serial No. 72,105.

This invention relates to a charging and distributing device for internal combustion engines. It has to do particularly with the provision of novel means for controlling the introduction of purified air to engines having a plurality of carburetors, although it will be understood that this invention is applicable to engines having one or more carburetors. This application is a division of 10 my prior pending application No. 748,119 filed November 6, 1924, now Patent No. 1,576,301, granted March 9, 1926.

It has heretofore been the practice, in designing L-head motors of the poppet valve 15 type, to place the exhaust and intake manifolds on the same side of the motor, but in T-head motors of the poppet valve type and in practically all sleeve valve motors, it has been customary to place the exhaust and intake 20 conduits on opposite sides of the cylinder block. Where motors have been designed utilizing a large number of cylinders and in particular straight eight cylinder motors, it has been customary to provide two carburetors for supplying the fuel to the cylinders. 25

One type of internal combustion engine having a large number of cylinders and a plurality of carburetors for supplying fuel to such cylinders is disclosed in my said prior 30 application No. 748,119. In this prior application the carburetors are arranged on opposite sides of the motor and the intake and exhaust manifolds are so arranged in combination with the carburetors as to completely 35 eliminate the difficulty of transferring the hot gases from one side of the cylinder block to the other. The present invention is primarily directed to the supplying of air to internal combustion engines of the general type disclosed in my said prior application. 40

More particularly the present invention relates to the provision of an engine cover positioned upon the cylinder block, an air cleaner for introducing purified air to the 45 space enclosed by the engine cover and means for conducting the air from the cover to one or a plurality of carburetors. This novel arrangement presents a rigid, compact structure and eliminates the necessity of providing 50 a separate air cleaner on each side of the motor or for each carburetor and also serves

to eliminate the piping which would otherwise necessarily be distributed over and around the engine block.

In the drawings:

Fig. 1 is a plan view of my novel air cleaner and distributing arrangement applied to an internal combustion engine having two carburetors.

Fig. 2 is a side elevation of the structure 60 illustrated in Fig. 1.

Fig. 3 is a cross sectional view of the motor shown in Figs. 1 and 2 and showing the cover for the cylinder block and the novel arrangement of the air cleaner and conduits for conducting the air from the cover to the carburetors.

In the drawings I have shown my novel air charging and distributing device in combination with a straight eight motor having carburetors *a*—*a* located on the opposite sides of the cylinder block and distributed and positioned at the opposite ends of the block. In this particular illustration the carburetors are shown located mid-way between each set of cylinders, that is, one carburetor in the center of each set of four cylinders. This is illustrated in Fig. 3 wherein at the right hand side of such figure the manifold is shown in central cross section.

As shown in Fig. 1 the carburetor and intake manifold at the rear of the motor bears the same relation to the rear set of cylinders as the carburetor on the opposite side bears to the front set of four cylinders. It will be understood however, that as far as the present invention is concerned the carburetors may be positioned in any desired relation with respect to the cylinders or sets of cylinders. In the particular arrangement as shown in the drawings, it will be noted that the front set of cylinders are connected by means of the exhaust pipes *e* to an exhaust manifold *d* leading to one carburetor for pre-heating the same, and that the other cylinders are provided with similar exhaust pipes *e* and an exhaust manifold *d* for similarly conducting the exhaust gases to the other carburetor.

In the higher class cars it is now desirable to employ an air cleaner to separate the suspended particles of dust and grit which would otherwise be drawn into the cylinder.

With a carburetor on each side or with a plurality of carburetors positioned as desired, it has been necessary either to utilize two air cleaners or provide a conduit system arranged over and around the cylinder block for introducing cleansed air into the carburetors. I have solved the difficulty by providing a suitable cover plate *g* for forming an air chamber along the top of the cylinder block. In the drawings, this chamber is shown as being fitted down over a pair of air conduits or elbows *j*, the cover plate being notched for this purpose. An air cleaner *h* of any desired type may be detachably connected to the top of the cover plate *g* by screw threads or otherwise, as best shown in Fig. 2. A pair of hand operated screws *i* are preferably provided for holding the cover plate in position in the usual manner.

In operation the air is drawn through the air cleaner in the usual manner and then drawn into the chamber formed by the cover plate *g*. From the chamber formed by this cover plate *g* the air may be drawn into both carburetors by means of the manifolds *j*. As the air is drawn into this common chamber it is heated by the top of the cylinder block. This in cold weather approximates more nearly a summer heat, which is a beneficial heat condition of the air, as it is not unduly heated as is the case if the air is unduly heated by some kind of a stove along the gas manifold. Furthermore, the circulation of air which is drawn in at considerable velocity around the plugs, has a beneficial effect in keeping the plugs cool.

This invention has been illustrated and described in connection with a straight eight motor, but it will be understood that the number and arrangement of the cylinders as well as the carburetors, may be varied as desired without changing the scope of the invention.

It will thus be seen that I have provided a novel air charging and distributing construction which is decidedly simple and compact in construction and arrangement, and which may be particularly utilized in connection with motors having a plurality of carburetors for efficiently collecting and conducting purified air to the carburetors.

What I claim is:

1. In an internal combustion engine, the combination of a plurality of cylinders, a spark plug for each cylinder, and electrical wiring connections for the spark plugs, a carburetor for furnishing the fuel supply to said cylinders, and a cover plate in the form of a cap bridging over both the entire plugs and the wiring connections, means for removably securing the cover plate onto the top of the engine, a conduit leading from the carburetor to the interior of the cover plate, and an air cleaner supported on the cover plate and arranged to filter the air drawn over the plugs and then into the carburetor.

2. In an internal combustion engine, the combination of a plurality of cylinders, a carburetor for furnishing fuel supply to said cylinders, a conduit leading from a position above the said cylinders to the carburetor, a plurality of spark plugs on the tops of said cylinders, together with wiring connections with said plugs, a cover plate fitting over the top of the cylinders and bridging completely over the plugs and the wiring, and fitting removably over the said conduit leading into the carburetor, means detachably holding the cover plate on the top of the cylinder over the conduit, and an air cleaner supported on the said cover plate and purifying the air admitted into the interior of the cover plate and thence to the carburetor.

In testimony whereof I have affixed my signature.

JAMES SCRIPPS BOOTH.
